QUENCHING AND CONVEYING APPARATUS

Robert E. Buckholdt, Salem, Ohio, assignor to
 The Salem Engineering Company, Salem, Ohio,
 a proprietorship

Application February 13, 1943, Serial No. 475,780

2 Claims. (Cl. 134—133)

1

This invention relates to material handling apparatus and more particularly to an assembly which is operative to quench and/or convey metal objects such as billets and ordnance shells for example. The apparatus of the invention is of particular utility in the metal heat treating art and may be advantageously employed intermediate hardening and draw furnaces. While the apparatus is designed particularly for and will be described in connection with the quenching of such objects upon the discharge from a hardening furnace it will become apparent, as the description proceeds, that the apparatus may be advantageously employed simply as a conveying or transferring device without the added function of quenching or immersing the objects.

In producing large quantities of heat treated shells, billets and similar metal objects it is common practice to provide the heating furnaces with a plurality of spaced parallel troughs or channels extending longitudinally through the furnaces. The objects are pushed through the furnaces in abutting relation and slide down inclined troughs at the discharge ends of the furnaces. It is one of the principal objects of the present invention to provide an improved object transferring apparatus which is operative to maintain the longitudinal alignment of the objects in the respective parallel rows during the transition of the objects from a furnace or other processing equipment to a second furnace or a second other processing device. In this manner the flow of the objects along the entire extent of the processing line is facilitated and uniformity of result in the products is assured. Moreover, individual handling of the objects is eliminated and, if desired, the processing line may be made entirely automatic.

Another object of the invention is the provision of an improved unitary and portable assembly which is of general utility in connection with a metal object treating plant. The apparatus of the invention employs a tank as the primary support for the operative elements of the apparatus, and in practice, this tank may be readily employed for quenching, oiling, washing, and for other purposes involving the immersion of the objects in a liquid. If desired, however, the tank may be left empty in which case the apparatus may serve simply as a conveying or transferring unit but in either case the operation of the apparatus is such that the objects progress therethrough in an orderly and controlled manner. This mode of operation, in addition to facilitating the charging of the next subsequent furnace or equipment in the processing line, has the further and important

advantage of being positive, i. e., the object or parts being handled are not allowed to roll or slip, thus clogging or fouling the equipment, and in addition, the parts or objects arrive at their discharge positions in proper timed sequence to be engaged by the charging mechanism of the succeeding furnace or equipment.

The above and other objects and advantages of the invention will become apparent upon consideration of the following detailed specification and the accompanying drawing wherein there is specifically disclosed a preferred embodiment of the invention.

The single figure of the drawing is a longitudinal section of an apparatus constructed in accordance with the principles of the invention. Reference numeral 10 indicates a tank of more or less conventional construction in which the walls are formed of metal sheets or plates suitably braced by metal angles or other suitable section. Tank 10 is supported on a base consisting principally of the beams 11.

25 A transversely extending tube 12 is rotatably mounted on the lower central portion of the tank 10 and liquid under pressure is supplied to the space within the tube 12 by the flexible pipe 13 having an inlet conduit 14 arranged to be connected to the outlet of a pump, not shown. While the apparatus of the invention normally employs 30 a plurality of laterally spaced parallel paths or channels of movement through the apparatus, the paths or channels are identical and therefore but one is shown in the drawing and but one will be described.

35 Welded or otherwise rigidly connected to the tube 12 is a bracket 15 to which is secured an extended nozzle or jet 16. Nozzle 16 is connected to the space within the tube by the conduit 17. Also rigidly secured to the rotatable tube 12 is 40 a member 18 having diametrically opposed wings arranged to engage the stops 19 to limit the extent of rotation of the tube in either direction. Pivoted connected with the member 18 is a link 20, the upper end of which is secured to the rod 45 21 of a piston, not shown, housed in the cylinder 22. Cylinder 22 is pivoted at 23 and it should be apparent that upon the application of fluid pressure to the lower end of cylinder 22 the member 18 and tube 12 will be rotated in a clockwise direction, as viewed in the drawing, until the right wing of the member 18 engages the right stop 19. Conversely, the application of fluid pressure to the upper end of cylinder 22 will move the tube 12 and bracket 15 back to the position shown in the drawing.

Aligned with the counter-clockwise position of the nozzle 16 is a trough 24 along which the objects to be quenched, oiled, washed or transferred are adapted to slide after passing down the conveyor or chute 25. The latter may, for example, be associated with the discharge end of a hardening furnace of the pusher type and it will be understood that upon each actuation of the pusher an object will slide down the members 25 and 24. To avoid damaging impact of the objects against the brackets 15 a brake is associated with the trough 24 to decelerate the objects before they reach the brackets 15. This brake consists of a shoe 26 pivoted at its upper end at 27 and having a tapered ceiling 28 which engages the tops of the objects as the latter slides down the trough 24. To the lower end of the shoe is secured a weight 29 which may be varied to vary the friction applied between the surface 28 and the shells or other objects having sliding movement relative thereto. A chain 30 limits the downward pivotal movement of the shoe 26 but is sufficiently long so as not to interfere with the frictional interengagement between the surface 28 and the objects.

Extending upwardly and outwardly of the tank 10 from a position adjacent the rotatable tube 12 is a trough or tube 31 having a slit opening 32 in its bottom portion extending the entire length of the trough or tube. Slideably received in the slit 32 are the spaced dogs 33, each of which is provided with a pin 34 pivotally connecting it on a slide or carrier 35. Suitable means, not shown, is employed to support and guide the carrier or slide 35 for reciprocating movement along a path parallel with the longitudinal axis of the tube 31. Such movement is imparted by an elongated cylinder 36, the piston rod 37 of which is connected to the slide 35. In the drawing the slide 35 and the dogs 33 are shown as approaching their upper limiting positions and upon release of pressure in the lower end of cylinder 36 the slide will retract until the lowermost dog thereon reaches the position in which it is shown in dotted lines in the drawing. It will be noted that the dogs 33 are of the retractable or gate type so that they are operative to propel objects up the tube 31. To retain the objects in their advanced positions as attained by the dogs 33 a pair of longitudinally spaced latches 38 are provided. It will be observed that the latches 38 lock the objects against downward movement while enabling said objects to progress up the tube.

As shown, the lower portion of the tube 31 is cut away at 39 and is so oriented with respect to the nozzle 16 carried by the bracket 15 that upon clockwise rotation of the tube 12 and bracket 15 a shell or other object on the nozzle 16 will be laid in the lower cut-away portion of the tube. If now the slide 35 is in lowermost position and cylinder 36 is actuated to move the slide upwardly the lowermost dog 33 will engage against the lower end of the said object and move the same up the tube. The length of stroke of the cylinder 36 is sufficient to insure that the lower end of the object is moved past the shoulder on the lower latch 38 whereupon this latch prevents the object from sliding back down the tube upon retraction of the slide 35. During the next succeeding outward stroke of the slide the object is lifted from the lower latch 38 to above the upper latch 38 while a second object is brought to above the lower latch 38. Upon the next outward stroke the first object will be transferred from above the upper latch 38 onto the trough 40 where it

will assume a horizontal position in the trough. From this position the object may be moved longitudinally into a second furnace or other equipment by a pusher 41 as will be well understood.

5 In practice, the operation of cylinders 22, 36 and 41 and, in addition, the pusher cylinder the action of which discharges objects into the trough 25 if such pusher cylinder is employed, are synchronized so that the operation of the 10 entire line may be automatic. Thus after an object is impaled on the nozzle 16 cylinder 22 is actuated to transfer the object to the tube 31. The retracted cylinder 36 is then actuated to move the object away from the nozzle 16 and to 15 a position above the lower latch 38 after which both the cylinders 22 and 36 may be actuated in a reverse direction to return their operated parts back to their initial starting positions. An 20 important result of the operation of the present apparatus is that the objects may be progressed through the immersion apparatus or transferred from one piece of equipment to another in a spaced, orderly, and step by step manner whereby all danger of fouling or clogging the mechanism is eliminated while at the discharge end 25 of the apparatus conventional pushers may, if desired, be employed to effect automatically the continuance of the travel of the objects.

While the invention has been illustrated and 30 described as applied to the quenching of tubular ordnance shells in which adaptation the jet 16 is of particular utility in furnishing a large volume of coolant to the inner surfaces of the shells, it will be apparent that the identical apparatus 35 illustrated may also be used in quenching, oiling, washing, or other treatment involving the application of liquid or simply conveying other hollow objects. If solid objects, as round or square billets, for example, are to be processed or handled the nozzle 16 is replaced by a suitable holder which engages the outer periphery of the object being handled and which may, if desired, include provisions for impinging a jet or jets of liquid supplied by the tube 12 against the outer surface 45 of the object. In any embodiment, it will be understood that a side edge of the bracket 15 is sufficiently offset or the bracket is provided with a slot to enable the lower dog 33 to strip the objects off the nozzles 16 or other retaining means employed.

Both the transferring mechanism 12-23 and the elevating mechanism 31-40 of the assembly are preferably made removable from the assembly as an integral unit without requiring the oil 55 or other liquid held in the tank 10 to be first drained. This feature is of distinct advantage in servicing or maintaining the apparatus, or in changing over the apparatus to handling a different type of object, particularly when it is considered that, in practice, the tank may be supplied with upwards of eight hundred gallons of liquid. The pumping out of this liquid would require additional pumping and storage facilities.

To enable the transferring mechanism 12-23 65 to be removed from the tank as a unit the same is assembled on a frame consisting of two spaced parallel vertically extending channel members 42 connected at their upper portions to a pair of spaced horizontally disposed channels 43. 70 Each of the channels 42 is slideably received in a guideway formed by two spaced angles 44 which are fastened to the side wall of the tank 10. It will be observed that the tube 12 is journaled in supports, of which there are at least two, and these supports are in turn mounted on trans-

versely extending members 45 which are welded to or otherwise suitably fastened at their ends to the lower portions of the channels 42. As indicated, channels 43 extend out over the tops of the side walls of the tank 10 and rest on blocks 46 secured to the top edges of the side walls. The entire transfer assembly 12-23 is thus suspended from the beams 43 and by engaging these beams with a crane, for example, this mechanism may be lifted bodily out of the tank and out of the liquid contained therein. Likewise, the elevating mechanism 31-40, is built as an integral unit, being slideably received and supported in the tank on the inclined angles 41 which are fastened to the inner surfaces of the side walls of the tank.

In the normal operation of the apparatus, it will be observed that the objects will be held by each of the latches 38 for an appreciable length of time. The upper latch 38, being well above the level of the liquid in the tank 10, will hold the objects in draining position for an appreciable length of time. There is thus provided a drainage period which allows excess oil or other liquid to drain off the objects before they are deposited in the trough 40. This is of advantage in most cases and particularly if the objects are to be charged from the trough 40 into a draw furnace. After draining, the objects are further elevated by the uppermost dog 38 and upon reaching a predetermined elevated position overbalance and fall into the trough 40, all as explained above. The apparatus of the invention enables the trough 40 to be positioned in line with the path of travel of the objects through the draw furnace or other falling equipment thus further simplifying the construction and operation of the complete processing line.

The invention herein disclosed is susceptible of embodiment in various arrangements and the above specifically described embodiment should therefore be taken as illustrative only. Reference should be made to the prior state of the art and to the spirit and scope of the appended claims in determining the scope of the invention.

I claim:

1. Apparatus of the character described comprising in combination a downwardly inclined trough, a rotatable transfer device arranged to receive objects from said trough, means comprising a brake shoe to decelerate said objects before they reach said device, an upwardly inclined trough extending from a position adjacent said

device, said device including means to impinge a stream of liquid onto said objects and being operative to position said objects on said upwardly inclined trough, a removable frame mounting said device, a cylinder on said frame for rotating said device, an elongated slide positioned below said last mentioned trough and mounted for reciprocating movement parallel with said last mentioned trough, means comprising a fluid pressure cylinder positioned below said slide to reciprocate the same, a plurality of spaced retractable dogs carried by said slide and operative during upward movement of the same to advance said objects along said last mentioned trough, and a plurality of retractable latches fixed with respect to said last mentioned trough and adapted to retain said objects in advanced positions whereby said objects may be advanced therealong in step by step progression.

2. In apparatus of the character described having a tank, a downwardly inclined guiding support extending into said tank, a unitary assembly comprising a movable object transferring member and means to move said member slideably received in said tank in vertically extending guideways, said member being adapted to receive objects from said support, a second unitary assembly extending into said tank and having an upwardly inclined guiding support adapted to receive objects from said member together with means to move said objects up said upwardly inclined support, vertically extending guideways in said tank for receiving said first mentioned assembly, said first mentioned assembly being removable from said tank as a unit.
